6-NITRO-2-SUBSTITUTED-BENZOTHIADIAZINES
 Jerry E. Robertson, Frank Di Pierro, and John H. Biel,
 Milwaukee, Wis., assignors to Colgate-Palmolive Company,
 a corporation of Delaware
 No Drawing. Filed June 15, 1961, Ser. No. 117,288
 20 Claims. (Cl. 167—65)

This invention relates to chemical compounds and processes of producing the same. More particularly, this invention is concerned with novel derivatives of benzothiadiazine, their preparation and uses.

This application is a continuation-in-part of copending application Serial No. 35,913, filed June 14, 1960, now abandoned, and of copending application Serial No. 74-229, filed December 7, 1960.

According to the present invention there are provided novel 2-substituted benzothiadiazines of the formulas

and

wherein R_2 is a lower alkyl such as methyl, ethyl, propyl and butyl, halo-lower alkyls such as β,β,β -trifluoroethyl, a lower alkenyl such as allyl, a lower alkynyl such as propargyl, a di-lower alkyl amino-lower alkyl group such as dimethylaminoethyl, phenyl, a phenyl-lower alkyl in which the lower alkyl is straight or branched and the phenyl is unsubstituted or substituted such as with one or more halo, nitro, lower alkoxy, lower alkyl or hydroxy groups such as the benzyl, phenethyl, phenylisopropyl, phenylpropyl, *p*-methylbenzyl and *p*-chlorophenethyl groups, a phenyl-lower alkenyl group such as cinnamyl, R_3 is hydrogen, a lower alkyl such as methyl, ethyl, propyl, isopropyl and butyl, a halo-lower alkyl such as chloromethyl, dichloromethyl, trifluoromethyl and beta-bromoethyl, an aralkyl group and particularly a phenyl-lower alkyl in which the lower alkyl is straight or branched and the phenyl is unsubstituted or substituted such as with one or more halo, nitro, lower alkoxy, lower alkyl or hydroxy groups such as benzyl, phenethyl, para-methoxyphenylethyl and diphenylmethyl, a cycloalkyl-lower alkyl such as cyclopentylmethyl and cyclohexyl-ethyl and other such groups in which the cycloalkyl has 5 to 7 carbons in the ring, a cycloalkenyl-lower alkyl in which the cycloalkenyl has 5 to 7 carbons in the ring such as 3-(cyclohexene)-methyl and cycloalkadienyl-lower alkyl groups in which the cycloalkadienyl has 5 to 7 carbons in the ring such as 5-(1,3-cyclopentadienyl)-methyl, Y is a chemical bond or a straight or branched lower alkylene as of 1 to 8 carbon atoms such as methylene, ethylene and propylene and Z is a lower alkyl such as methyl, ethyl, isopropyl, propyl, butyl, isobutyl, tertiary butyl and amyl, an aryl group such as phenyl and substituted phenyl groups like halophenyl, lower alkoxy-phenyl and lower alkyl-phenyl, aralkyl groups such as phenyl-lower alkyl groups like benzyl and phenylethyl, or a halo-lower alkyl such as chloromethyl, dichloromethyl and bromophenyl.

The compounds of this invention can be produced by reacting an appropriate 2,4-disulfamylaniline with an aldehyde. In forming the compounds of Formulas I and

2

II above, the same process is used although with different reactants. These processes will be illustrated separately to maintain simplicity.

The process of forming the compounds of Formula I 5 can be represented as follows:

wherein R_2 , R_3 and R_4 have the assigned significance.

The compounds of Formula II can be produced by reacting an appropriate 2,4-disulfamylaniline with a keto-aldehyde or ketoacetal. The reaction can be represented 20 as follows:

wherein R_2 , Y and Z have the significance previously assigned and R_4 is a lower alkyl such as methyl or ethyl.

Some of the 2-substituted-2,4-disulfamylaniline derivatives which can be used in this reaction are:

- 2-methylsulfamyl-4-sulfamyl-5-nitro-aniline,
- 2-ethylsulfamyl-4-sulfamyl-5-nitro-aniline,
- 2- β,β,β -trifluoroethylsulfamyl-4-sulfamyl-5-nitro-aniline,
- 2-allylsulfamyl-4-sulfamyl-5-nitro-aniline,
- 2-propargylsulfamyl-4-sulfamyl-5-nitro-aniline,
- 2-benzylsulfamyl-4-sulfamyl-5-nitro-aniline,
- 2-(beta-dimethylaminoethyl)-sulfamyl-4-sulfamyl-5-nitro-aniline,
- 2-(beta-phenethyl)-sulfamyl-4-sulfamyl-5-nitro-aniline,
- 2-phenylsulfamyl-4-sulfamyl-5-nitro-aniline,
- 2-cyclohexylmethylsulfamyl-4-sulfamyl-5-nitro-aniline,
- 2-cyclopentylmethylsulfamyl-4-sulfamyl-5-nitro-aniline,
- 2-(para-methoxybenzyl)-sulfamyl-4-sulfamyl-5-nitro-aniline,
- 2-(beta-p-chloro-phenethyl)-sulfamyl-4-sulfamyl-5-nitro-aniline,
- 2-buteneylsulfamyl-4-sulfamyl-5-nitro-aniline and
- 2-penteneylsulfamyl-4-sulfamyl-5-nitro-aniline.

Some of the aldehydes, or equivalent acetals, which can be used in the process are formaldehyde, acetaldehyde, propionaldehyde, *n*-valeraldehyde, caproaldehyde, benzaldehyde, phenylacetaldehyde, beta-phenylpropionaldehyde, beta-methoxypropionaldehyde, diphenylacetaldehyde, *p*-chlorophenylacetaldehyde diethyl acetal, bromoacetaldehyde diethyl acetal, dichloroacetaldehyde, trifluoroacetaldehyde, phenylacetaldehyde dimethylacetal, dichloroacetaldehyde and chloroacetal.

In addition, ketoaldehydes and their equivalent ketoacetals can also be employed in the process. Some of the ketoaldehydes which can be used, either as the free aldehyde or as an acetal, are 3-ketobutyraldehyde-1-dimethylacetal, pyruvaldehyde, dichloropyruvaldehyde, levulinaldehyde, trifluoromethylpyruvaldehyde, 4-phenyl-3-ketobutyraldehyde dimethylacetal, 3-ketohexanal-1,4-keto-8-chloro-octanal-1 and 2-keto-5-phenyl-pentanal-1,

4-(para-nitrophenyl)-3-ketobutyraldehyde, 4-(para-trifluoromethylphenyl)-3-ketobutyraldehyde and 4-(meta-chlorophenyl)-3-ketobutyraldehyde, 3-ketopentanal, 4-ketohexanal, and 3-keto-3-phenylpropanal.

The compounds of this invention can be produced by reacting the appropriate 2,4-disulfamylaniline with the appropriate aldehyde in the presence of a suitable inert organic reaction medium such as dimethyl formamide and at a moderately elevated temperature such as from about 70 to 150° C. Water can be present in the reaction mixture. A catalytic amount of an acid such as aqueous hydrochloric acid or p-toluenesulfonic acid is included in the reaction mixture to promote the reaction. The reaction is generally completed in about one-half to three hours. After the reaction is terminated, the solvent is removed as by evaporation under reduced pressure, the residue taken up in alcohol and crystallized from aqueous alcohol.

Some of the 2-substituted benzothiadiazines which are produced as described are:

2-allyl-3,4-dihydro-6-nitro-7-sulfamyl-1,2,4-benzothiadiazine-1,1-dioxide,
 2-propargyl-3,4-dihydro-6-nitro-7-sulfamyl-1,2,4-benzothiadiazine-1,1-dioxide,
 2-benzyl-3,4-dihydro-6-nitro-7-sulfamyl-1,2,4-benzothiadiazine-1,1-dioxide,
 2-phenethyl-3,4-dihydro-6-nitro-7-sulfamyl-1,2,4-benzothiadiazine-1,1-dioxide,
 2-allyl-3-methyl-3,4-dihydro-6-nitro-7-sulfamyl-1,2,4-benzothiadiazine-1,1-dioxide,
 2-propargyl-3-ethyl-3,4-dihydro-6-nitro-7-sulfamyl-1,2,4-benzothiadiazine-1,1-dioxide,
 2-benzyl-3-phenethyl-3,4-dihydro-6-nitro-7-sulfamyl-1,2,4-benzothiadiazine-1,1-dioxide,
 2-phenethyl-3-chloromethyl-3,4-dihydro-6-nitro-7-sulfamyl-1,2,4-benzothiadiazine-1,1-dioxide,
 2-benzyl-3-dichloromethyl-3,4-dihydro-6-nitro-7-sulfamyl-1,2,4-benzothiadiazine-1,1-dioxide,
 2-allyl-3,4-dihydro-3-(beta-keto-n-propyl)-6-nitro-7-sulfamyl-1,2,4-benzothiadiazine-1,1-dioxide,
 2-allyl-3-acetyl-3,4-dihydro-7-sulfamyl-6-nitro-1,2,4-benzothiadiazine-1,1-dioxide,
 2-benzyl-6-nitro-3,4-dihydro-3-(beta-keto-n-propyl)-7-sulfamyl-1,2,4-benzothiadiazine-1,1-dioxide,
 2-phenethyl-3,4-dihydro-6-nitro-3-(beta-keto-n-propyl)-7-sulfamyl-1,2,4-benzothiadiazine-1,1-dioxide,
 2-allyl-3-acetyl-6-nitro-3,4-dihydro-7-sulfamyl-1,2,4-benzothiadiazine-1,1-dioxide,
 2-benzyl-3,4-dihydro-6-nitro-3-dichloroacetyl-7-sulfamyl-1,2,4-benzothiadiazine-1,1-dioxide,
 2-allyl-3,4-dihydro-6-nitro-3-(gamma-phenyl-beta-keto-propyl)-7-sulfamyl-1,2,4-benzothiadiazine-1,1-dioxide,
 2-phenylisopropyl-3,4-dihydro-6-nitro-3-(gamma-trifluoromethyl-phenyl-beta-keto-propyl)-7-sulfamyl-1,2,4-benzothiadiazine-1,1-dioxide,
 2-propargyl-3,4-dihydro-6-nitro-3-(gamma-keto-butyl)-7-sulfamyl-1,2,4-benzothiadiazine-1,1-dioxide,
 2-propargyl-3,4-dihydro-6-nitro-3-(beta-keto-propyl)-7-sulfamyl-1,2,4-benzothiadiazine-1,1-dioxide,
 2-benzyl-3-acetyl-3,4-dihydro-6-nitro-7-sulfamyl-1,2,4-benzothiadiazine-1,1-dioxide,
 2-(beta-phenethyl)-3,4-dihydro-6-nitro-3-(beta-keto-beta-phenethyl)-7-sulfamyl-1,2,4-benzothiadiazine-1,1-dioxide,
 2-allyl-3,4-dihydro-6-nitro-3-propionyl-7-sulfamyl-1,2,4-benzothiadiazine-1,1-dioxide,
 2-cinnamyl-3,4-dihydro-3-(beta-keto-n-propyl)-6-nitro-7-sulfamyl-1,2,4-benzothiadiazine-1,1-dioxide,
 2-allyl-6-nitro-3,4-dihydro-3-(beta-keto-n-propyl)-7-sulfamyl-1,2,4-benzothiadiazine-1,1-dioxide,
 2-benzyl-3-acetyl-6-nitro-3,4-dihydro-7-sulfamyl-1,2,4-benzothiadiazine-1,1-dioxide,
 2-allyl-3,4-dihydro-6-nitro-3-dichloroacetyl-7-sulfamyl-1,2,4-benzothiadiazine-1,1-dioxide,

2-(beta-dimethylaminoethyl)-3,4-dihydro-6-nitro-3-(gamma-keto-butyl)-7-sulfamyl-1,2,4-benzothiadiazine-1,1-dioxide,
 2-benzyl-3,4-dihydro-6-nitro-3-(beta-keto-beta-phenethyl)-7-sulfamyl-1,2,4-benzothiadiazine-1,1-dioxide,
 2-benzyl-3,4-dihydro-6-nitro-3-propionyl-7-sulfamyl-1,2,4-benzothiadiazine-1,1-dioxide, and
 2-(beta-phenethyl)-3,4-dihydro-6-nitro-3-(gamma-keto-butyl)-7-sulfamyl-1,2,4-benzothiadiazine-1,1-dioxide.
 10 2 - methyl - 3,4 - dihydro-6-nitro-7-sulfamyl-1,2,4-benzothiadiazine-1,1-dioxide,
 2 - methyl - 3 - methyl - 3,4 - dihydro-6-nitro-7-sulfamyl-1,2,4-benzothiadiazine-1,1-dioxide,
 2 - propyl - 3 - ethyl-3,4-dihydro-6-nitro-7-sulfamyl-1,2,4-benzothiadiazine-1,1-dioxide,
 2 - methyl - 3 - phenethyl-3,4-dihydro-6-nitro-7-sulfamyl-1,2,4-benzothiadiazine-1,1-dioxide,
 2 - ethyl - 3-chloromethyl-3,4-dihydro-6-nitro-7-sulfamyl-1,2,4-benzothiadiazine-1,1-dioxide,
 20 2 - butyl - 3 - dichloromethyl - 3,4-dihydro-6-nitro-7-sulfamyl-1,2,4-benzothiadiazine-1,1-dioxide,
 2 - methyl - 3,4-dihydro-3-(beta-keto-n-propyl)-6-nitro-7-sulfamyl-1,2,4-benzothiadiazine-1,1-dioxide,
 25 2 - methyl - 3-acetyl-3,4-dihydro-7-sulfamyl-6-nitro-1,2,4-benzothiadiazine-1,1-dioxide,
 2 - ethyl - 6 - nitro-3,4-dihydro-3-(gamma-keto-butyl)-7-sulfamyl-1,2,4-benzothiadiazine-1,1-dioxide,
 2 - β,β,β - trifluoroethyl - 3,4-dihydro-6-nitro-3-(beta-keto-n-propyl)-7-sulfamyl-1,2,4-benzothiadiazine-1,1-dioxide,
 30 2 - methyl - 3,4 - dihydro - 6-nitro-3-dichloroacetyl-7-sulfamyl-1,2,4-benzothiadiazine-1,1-dioxide and
 2 - methyl - 3,4 - dihydro - 6-nitro-3-(gamma-phenyl-beta-keto-n-propyl)-7-sulfamyl-1,2,4-benzothiadiazine-1,1-dioxide.

These and other compounds of this invention are highly effective diuretic agents which promote the excretion of excess fluid and sodium chloride from animals and are, therefore, useful in the treatment of congestive heart failure. They are also hypotensive agents.

The compounds of this invention can be administered in pharmaceutical unit dosage forms formed by combining one or more of the active compounds with a pharmaceutical carrier and then manufacturing capsules, tablets and powders therefrom. Such unit dosage forms can contain about 5 to 500 mgm., and advisably 5 to 100 mgm., of one or more of the active compounds of this invention.

It had been thought that the reactants of the formula

used in the described process in which R_2 has the assigned meaning could be produced by reacting a 3-keto-7-sulfamyl-2H-1,2,4-benzothiadiazine-1,1-dioxide with an alkylating agent to produce a 2-substituted-3-keto-7-sulfamyl-1,2,4-benzothiadiazine-1,1-dioxide and treating said compound with a base to open the ring and form a 2-substituted-sulfamyl-4-sulfamyl-aniline according to the scheme

as reported in J. Am. Chem. Soc. 82, 2042 (1960). Surprisingly, the compounds of the formula

wherein R₂ has the assigned meaning could not be produced by the process just described. It had been expected, however, that these reactants could be produced similar to the reaction of 5-chloroaniline-2,4-disulfonylchloride with monomethylamine followed by reaction with ammonia as shown in J. Am. Chem. Soc. 82, 1161 (1960) and which can be represented as follows:

This process, however, did not function satisfactorily when methylamine was replaced by ethylamine or benzylamine. Also, it could not be applied successfully to 5-nitroaniline-2,4-disulfonylchloride.

It has been found, however, that the compounds of the formula

where R₂ has the assigned meaning, can be prepared by reacting 5-nitroaniline-2,4-disulfonylchloride first with ammonia and then with the monosubstituted amine. This process can be represented as follows:

wherein R₂ has the assigned meaning.

The first step of the process is readily effected by bringing 5-nitroaniline-2,4-disulfonylchloride into contact with ammonia, advisably in a suitable solvent and particularly ethanol. The ammonia can be suitably employed dissolved in the ethanol. The reaction proceeds readily at room temperature and can be considered complete in 0.5 to 1 hour. The monosubstituted amine can then be added as in ethanol solution, to the reaction mixture. This reaction also proceeds at room temperature but slightly elevated temperatures serve to promote the reaction. The desired product can be recovered by diluting the reaction mixture with water and partially evaporating the solution to precipitate out the product.

Some of the monosubstituted amines which can be used in the process are methylamine, ethylamine, propylamine, isopropylamine, allylamine, benzylamine, phenethylamine, aniline, β,β,β -trifluoroethylamine, propargylamine, dimethylaminoethylamine and cinnamylamine.

Some of the products obtained as described are:

2-methylsulfamyl-5-nitro-4-sulfamylaniline,
2-ethylsulfamyl-5-nitro-4-sulfamylaniline,
2-propylsulfamyl-5-nitro-4-sulfamylaniline,
2-allylsulfamyl-5-nitro-4-sulfamylaniline,
2-(β,β,β -trifluoroethylsulfamyl)-5-nitro-4-sulfamylaniline,

2-phenylsulfamyl-5-nitro-4-sulfamylaniline,
2-benzylsulfamyl-5-nitro-4-sulfamylaniline and
2-(beta-phenethyl)-sulfamyl-5-nitro-4-sulfamylaniline.

The following examples are presented to illustrate the invention.

Example 1.—2-methylsulfamyl-5-nitro-4-sulfamylaniline

To a stirred suspension of 8.5 g. (0.025 mole) of 5-nitronaniline-2,4-disulfonylchloride in 50 ml. of ethanol at room temperature was added 39 ml. of cold 1.27 N ethanolic ammonia (0.050 mole) over one hour. After stirring for an additional hour, 6.0 g. (0.180 mole) of monomethylamine in 50 ml. of ethanol was added to the mixture containing 5-nitroaniline-4-sulfamyl-2-sulfonylchloride and the reaction mixture was held at 30-35° C. for one hour. Dilution with 500 ml. of water, concentration in vacuo to about 400 ml., and cooling gave a solid which was collected and recrystallized from water to afford 4.0 g. (55%) of product, M.P. 176°-180° C. (dec.)

Analysis.—Calcd. for C₇H₁₀N₄S₂O₆: S, 20.65. Found: S, 20.53.

Example 2.—2-ethylsulfamyl-5-nitro-4-sulfamylaniline

A procedure identical to that given in Example 1 was used except that 0.18 mole of ethylamine was used in place of methylamine. The product was obtained in 75% yield, M.P. 168°-171° C.

Analysis.—Calcd. for C₈H₁₂N₄O₆: N, 17.28; S, 19.75. Found: N, 17.42; S, 20.09.

Example 3.—2-propylsulfamyl-5-nitro-4-sulfamylaniline

To a stirred suspension of 8.5 g. (0.025 mole) of 5-nitroaniline-2,4-disulfonyl chloride in 50 ml. of ethanol at 20° C. was added 10 ml. of cold 5.07 N ethanolic ammonia (0.050 mole) over about one hour. After stirring at about 20° C. for an additional hour, 5.9 g. (0.10 mole) of n-propylamine was added in one portion. The resultant exothermic reaction was controlled with an ice water bath. After one hour of standing at room temperature, the reaction mixture was reduced in vacuo in about one-half of the original volume and then poured into 300 ml. of water. After standing at room temperature for two days, the solid which separated was collected by filtration, washed with water, dried and pulverized to afford 6.0 g. (71%) of product, M.P. 148-153° C. (dec.)

Analysis.—Calcd. for C₉H₁₄N₄O₆S₂: N, 16.57; S, 18.93. Found: N, 16.10; S, 18.61.

Example 4.—3,4 - dihydro - 2 - methyl - 6 - nitro - 3 - (beta - ketopropyl) - 7 - sulfamyl - 1,2,4 - benzothiadiazine - 1,1 - dioxide

2-methylsulfamyl-5-nitro-4-sulfamylaniline (4.1 g., 0.013 mole), 1.9 g. (0.014 mole) of 3-ketobutyraldehyde dimethylacetal, and 1.0 ml. concentrated HCl were dissolved in 25 ml. of dimethyl formamide and then held at 90°-100° C. for 30 minutes. The solvent was removed in vacuo and the residue dissolved in about 60 ml. of hot ethanol. After filtration, hot water was added to the cloud point (about 120 ml.) and the solution cooled. A solid separated which afforded 3.5 g. (71%) of product, M.P. 215°-217° C.

Analysis.—Calcd. for C₁₁H₁₄N₄O₇S₂: S, 16.94; N, 14.82. Found: S, 16.85; N, 14.66.

Example 5.—3 - benzyl - 3,4 - dihydro - 2 - methyl - 6 - nitro - 7 - sulfamyl - 1,2,4 - benzothiadiazine - 1,1 - dioxide

2-methylsulfamyl-5-nitro-4-sulfamylaniline (4.1 g., 0.013 mole), 2.3 g. (0.014 mole) of phenylacetaldehyde dimethylacetal, and 1.0 ml. of concentrated hydrochloric acid were dissolved in 25 ml. of dimethylformamide and held at 90-100° C. for 1.5 hours. The solvent was removed in vacuo and the residue dissolved in about 60 ml. of hot ethanol, the solution was filtered, and hot water was added to the cloud point (about 10 ml.). Cooling gave a solid which afforded 4.0 g. (76%) of product, M.P. 240-245° C.

Analysis.—Calcd. for $C_{15}H_{16}N_4O_6S_2$: S, 15.56; N, 13.59. Found: S, 15.33; N, 13.57.

Example 6.—3-benzyl-3,4-dihydro-2-ethyl-6-nitro-7-sulfamyl-1,2,4-benzothiadiazine-1,1-dioxide

2-ethylsulfamyl-5-nitro-4-sulfamylaniline (4.2 g., 0.013 mole) was condensed with phenylacetaldehyde dimethylacetal as in Example 5 to afford 4.1 g. (74%) (chloroform washed) of product, M.P. 207-212° C.

Analysis.—Calcd. for $C_{16}H_{19}N_4O_6S_2$: S, 15.06; N, 13.16. Found: S, 14.87; N, 13.19.

Example 7.—3-dichloromethyl-3,4-dihydro-2-methyl-6-nitro-7-sulfamyl-1,2,4-benzothiadiazine-1,1-dioxide

2-methylsulfamyl-5-nitro-4-sulfamylaniline (10.0 g., 0.032 mole), 5 ml. of concentrated hydrochloric acid and 3.7 g. (0.04 mole) of dichloroacetaldehyde (freshly distilled) were dissolved in 30 ml. of dimethylformamide and the solution was heated at 90-100° C. for 2.5 hours. The solvent was removed in vacuo and the residue dissolved in a solution of 5.0 ml. of concentrated hydrochloric acid in 100 ml. of ethanol (room temperature). Dilution of this solution with cool water to the cloud point (about 100 ml.) and further cooling gave after another similar recrystallization, 4.1 g. (32%) of product, M.P. 266-267° C. (dec., prior charring).

Analysis.—Calcd. for $C_9H_{10}Cl_2N_4O_6S_2$: Cl, 17.49; N, 13.83. Found: Cl, 16.96; N, 14.02.

Example 8.—3-chloromethyl-3,4-dihydro-2-ethyl-6-nitro-7-sulfamyl-1,2,4-benzothiadiazine-1,1-dioxide

2-ethylsulfamyl-5-nitro-4-sulfamylaniline (3.0 g., 0.0091 mole), 1.45 g. (0.0095 mole) of chloroacetal, and 0.5 ml. of concentrated hydrochloric acid were dissolved in 20 ml. of dimethylformamide and the solution held at 90-100° C. for 4 hours. The solvent was removed in vacuo and the residue crystallized and recrystallized from dilute ethanol to afford 2.1 g. (60%) of product, M.P. 217-218° C.

Analysis.—Calcd. for $C_{10}H_{13}ClN_4O_6S_2$: Cl, 9.21; S, 16.66. Found: Cl, 9.29; S, 16.49.

Example 9.—3,4-dihydro-2-ethyl-6-nitro-3-(beta-oxo-beta-phenylethyl)-7-sulfamyl-1,2,4-benzothiadiazine-1,1-dioxide

2-ethylsulfamyl-5-nitro-4-sulfamylaniline (4.5 g., 0.0137 mole), 2.0 ml. concentrated hydrochloric acid and 2.4 g. (0.014 mole) of the sodium salt of 3-keto-3-phenylpropanol were mixed in 25 ml. of dimethylformamide. After one hour at 90-100° C., the precipitated NaCl was collected and washed with dimethylformamide. The solvent was removed from the combined filtrate and washings to afford a gum which was crystallized and recrystallized from dilute ethanol and then from water-acetone to give 0.9 g. (14%) of product, M.P. 221-222° C.

Analysis.—Calcd. for $C_{17}H_{18}N_4O_7S_2$: C, 44.85; H, 3.90; N, 12.35. Found: C, 45.00; H, 4.00; N, 12.06.

Example 10.—2-benzylsulfamyl-5-nitro-4-sulfamylaniline

To a stirred suspension of 8.5 g. (0.025 mole) of 5-nitro-aniline-2,4-disulfonyl chloride and 50 ml. of ethanol at 20° C. was added 10 ml. of 5.07 N ethanolic ammonia (0.050 mole) diluted with 15 ml. of ethanol

over about one hour. After stirring at 20° C. for an additional hour, 10 g. (0.10 mole) of benzylamine was added in one portion. The exothermic reaction was controlled with an ice water bath. After stirring at 20-25° C. for another hour, the mixture was poured into 300 ml. of water and allowed to stand at room temperature overnight. The solid was collected, rinsed with water, dried, and ground under ether and then redried to afford 7.3 g. (75%) of product, M.P. 159-161° C.

Analysis.—Calcd. for $C_{13}H_{14}N_4O_6S_2$: S, 16.58. Found: S, 16.42.

Example 11.—5-nitro-4-sulfamyl-2-(β,β,β -trifluoroethyl-sulfamyl)-aniline

To a stirred suspension of 8.5 g. (0.025 mole) of 5-nitroaniline-2,4-disulfonyl chloride in 50 ml. of ethanol at 20° C. was added 10 ml. of 5.07 N ethanolic ammonia diluted with 15 ml. of ethanol over about 1 hour. After stirring at 20° C. for an additional hour, 13.5 g. (0.10 mole) of β,β,β -trifluoroethylamine hydrochloride was added in one portion and stirring was continued another 20 minutes. Triethylamine (10 g., 0.10 mole) was added in one portion with cooling and the mixture was stirred another hour at 20° C. Reduction of the volume by one-half in vacuo and dilution to about 300 ml. with water gave, after standing 2 days at room temperature, a solid. This material was collected, washed with water, dried, triturated with ether, and redried to afford 3.0 g. (32%) of product, M.P. 199-201° C.

Analysis.—Calcd. for $C_8H_9N_4O_6F_3$: N, 16.93; S, 14.81. Found: N, 17.10; S, 14.87.

Example 12.—3-benzyl-3,4-dihydro-6-nitro-7-sulfamyl-2-(β,β,β -trifluoroethyl)-1,2,4-benzothiadiazine-1,1-dioxide

5-nitro-4-sulfamyl-2-(β,β,β -trifluoroethyl)sulfamylaniline (3.8 g., 0.010 mole), 1.7 g. (0.010 mole) of phenylacetaldehyde dimethylacetal, and 0.5 ml. of concentrated hydrochloric acid were dissolved in 25 ml. of dimethylformamide and the solution was held at 90-100° C. for 4.5 hours. The solvent was removed in vacuo and the residue dissolved in about 60 ml. of hot ethanol. This solution was treated with activated charcoal, filtered, and diluted with hot water to the cloud point (about 30 ml.). Cooling gave a solid which was collected, washed with dilute ethanol and dried to afford 3.5 g. (70%) of product, M.P. 224-226° C.

Analysis.—Calcd. for $C_{16}H_{15}F_3N_4O_6S_2$: N, 11.28; S, 12.92. Found: N, 11.32; S, 12.88.

Example 13.—3-dichloromethyl-3,4-dihydro-6-nitro-7-sulfamyl-2-(β,β,β -trifluoroethyl)-1,2,4-benzothiadiazine-1,1-dioxide

5-nitro-4-sulfamyl-2-(β,β,β -trifluoroethyl)-sulfamylaniline (3.8 g., 0.010 mole), 1 drop of concentrated sulfuric acid and 1.4 g. (0.012 mole) of freshly distilled dichloroacetaldehyde were dissolved in 25 ml. of dimethylformamide and the solution held at 90-100° C. for 7 hours. The solvent was removed in vacuo and the residue dissolved in 70 ml. of ethanol. This solution was treated with activated charcoal, filtered, and diluted with 50 ml. of concentrated hydrochloric acid and then water to the cloud point (about 50 ml.). Cooling gave a solid which was collected, washed with dilute ethanol, and dried to afford 2.9 g. (61%) of product, M.P. 236-238° C.

Analysis.—Calcd. for $C_{10}H_9Cl_2F_3N_4O_6S_2$: Cl, 14.98; S, 13.55. Found: Cl, 14.80; S, 13.87.

Example 14.—3-chloromethyl-3,4-dihydro-6-nitro-7-sulfamyl-2-(β,β,β -trifluoroethyl)-1,2,4-benzothiadiazine-1,1-dioxide

5-nitro-4-sulfamyl-2-(β,β,β -trifluoroethyl)-sulfamylaniline (3.0 g., 0.0080 mole), 1.4 g. (0.0090 mole) of chloroacetal, and 0.5 ml. of concentrated hydrochloric acid were dissolved in 25 ml. of dimethylformamide and the solution held at 90-100° C. for 6 hours. The solvent was removed in vacuo and the residue dissolved in 40 ml. of

hot ethanol. This solution was treated with activated charcoal, filtered, and diluted with 100 ml. of hot water. Cooling gave a solid which was collected, washed with water and dried to yield 2.5 g. (71%) of product, M.P. 218-220° C.

Analysis.—Calcd. for $C_{10}H_{10}ClF_3N_4O_6S_2$: Cl, 8.08; S, 14.62. Found: Cl, 8.05; S, 14.59.

Example 15.—3,4-dihydro-3-(β -ketopropyl)-6-nitro-7-sulfamyl-2-(β,β,β -trifluoroethyl)-1,2,4-benzothiadiazine-1,1-dioxide

5-nitro-4-sulfamyl-2-(β,β,β -trifluoroethyl)sulfamylaniline (3.0 g., 0.010 mole), 1.5 g. (0.011 mole) of 3-ketobutyraldehyde-1-dimethylacetal, and 0.5 ml. of concentrated hydrochloric acid were dissolved in 25 ml. of dimethylformamide and the solution held at 90-100° C. for 20 minutes. The solvent was removed in vacuo and the residue dissolved in 60 ml. of hot ethanol. This solution was treated with activated charcoal, filtered, and diluted with hot water to about 120 ml. Cooling gave a solid which was collected and recrystallized from dilute ethanol to afford 1.8 g. (40%) of product, M.P. 191-195° C.

Analysis.—Calcd. for $C_{12}H_{13}F_3N_4O_7S_2$: N, 12.55; S, 14.36. Found: N, 12.66; S, 14.62.

Example 16.—3,4-dihydro-2-ethyl-3-(β -ketopropyl)-6-nitro-7-sulfamyl-1,2,4-benzothiadiazine-1,1-dioxide

2-ethylsulfamyl-5-nitro-4-sulfamylaniline (2.0 g., 0.00615 mole), 0.5 ml. of concentrated hydrochloric acid, and 1.1 g. (0.0080 mole) of 3-ketobutyraldehyde-1-dimethylacetal were dissolved in 20 ml. of dimethylformamide and the solution was held at 90-100° C. for 30 minutes. The solvent was removed in vacuo and the residue dissolved in 60 ml. of ethanol. This solution was treated with activated charcoal, filtered, and diluted to the cloud point with hot water (about 100 ml.). Cooling gave a solid which was collected, washed with water and dried to afford 1.4 g. (50%) of product, M.P. 196-199° C.

Analysis.—Calcd. for $C_{11}H_{14}N_4O_7S_2$: N, 14.32; S, 16.38. Found: N, 14.38; S, 16.51.

Example 17.—3-dichloromethyl-3,4-dihydro-2-ethyl-6-nitro-7-sulfamyl-1,2,4-benzothiadiazine-1,1-dioxide

2-ethylsulfamyl-5-nitro-4-sulfamylaniline (1.3 g., 0.0040 mole), 1 drop of concentrated sulfuric acid and 0.6 g. (0.0050 mole) of freshly distilled dichloroacetaldehyde were dissolved in 20 ml. of dimethylformamide and the solution was held at 90-100° C. for 6 hours. The solvent was removed in vacuo and the residue dissolved in 40 ml. of hot ethanol. The solution was treated with activated charcoal, filtered, diluted with about 100 ml. of concentrated hydrochloric acid and then 30 ml. of water. Cooling gave a small first crop of solid which was collected and discarded. The mother liquor was diluted with about 150 ml. of water and the solid which separated was collected, washed with cold water and dried to afford 0.8 g. of crude product. This material was dissolved in ethanol, reprecipitated with n-hexane, collected and re-dried to provide 0.4 g. (24%) of product, M.P. 222-224° C.

Analysis.—Calcd. for $C_{10}H_{12}Cl_2N_4O_6S_2$: C, 28.64; H, 2.89. Found: C, 28.62; H, 3.20.

Example 18.—2-benzyl-3-dichloromethyl-3,4-dihydro-6-nitro-7-sulfamyl-1,2,4-benzothiadiazine-1,1-dioxide

2-benzylsulfamyl-5-nitro-4-sulfamylaniline (2.6 g., 0.0067 mole), 1 drop of concentrated sulfuric acid and 0.90 g. (0.0080 mole) of freshly distilled dichloroacetaldehyde were dissolved in 25 ml. of dimethylformamide and the solution held at 90-100° C. for 6 hours. The solvent was removed in vacuo and the residue dissolved in 40 ml. of ethanol. The solution was treated with activated charcoal, filtered, diluted with 100 ml. of concen-

trated hydrochloric acid, and then about 30 ml. of water. Cooling gave a small first crop which was collected and discarded. Dilution of the mother liquor with about 150 ml. of water gave a second crop of solid which was collected, washed with water and dried. This crude product was dissolved in ethanol and reprecipitated with n-hexane to afford 0.9 g. (28%) of product, M.P. 222-223° C.

Analysis.—Calcd. for $C_{15}H_{14}Cl_2N_4O_6S_2$: C, 37.43; H, 2.93; N, 11.64. Found: C, 38.16; H, 3.25; N, 11.65.

Various changes and modifications of the invention can be made and, to the extent that such variations incorporate the spirit of this invention, they are intended to be included within the scope of the appended claims.

What is claimed is:

15. 1. A member of the group consisting of compounds of the formulas

wherein R_2 is a member of the group consisting of lower alkyl, halo-lower alkyl, lower alkenyl, lower alkynyl, di-lower alkyl amino-lower alkyl, phenyl, phenyl-lower alkyl and phenyl-lower alkenyl groups, R_3 is a member of the group consisting of hydrogen, lower alkyl, halo-lower alkyl, phenyl-lower alkyl, cycloalkyl-lower alkyl, in which the cycloalkyl has 5 to 7 carbon atoms, cycloalkenyl-lower alkyl, in which the cycloalkenyl has 5 to 7 carbon atoms, and cycloalkadienyl-lower alkyl groups, in which the cycloalkadienyl has 5 to 7 carbon atoms, Y is a member of the group consisting of a single chemical bond and lower alkylene groups and Z is a member of the group consisting of lower alkyl, phenyl, phenyl-lower and halo-lower alkyl groups.

2. 2-lower alkyl-3,4-dihydro-6-nitro-3-(β -keto-n-propyl)-7-sulfamyl-1,2,4-benzothiadiazine-1,1-dioxide.

3. 2-lower alkyl-3-acetyl-6-nitro-3,4-dihydro-7-sulfamyl-1,2,4-benzothiadiazine-1,1-dioxide.

4. 2-lower alkyl-6-nitro-3,4-dihydro-3-lower alkanone-7-sulfamyl-1,2,4-benzothiadiazine-1,1-dioxide.

45 5. 2-methyl-3,4-dihydro-3-(β -ketopropyl)-6-nitro-7-sulfamyl-1,2,4-benzothiadiazine-1,1-dioxide.

6. 2-methyl-3,4-dihydro-3-benzyl-6-nitro-7-sulfamyl-1,2,4-benzothiadiazine-1,1-dioxide.

7. 2-ethyl-3,4-dihydro-3-benzyl-6-nitro-7-sulfamyl-1,2,4-benzothiadiazine-1,1-dioxide.

50 8. 2-methyl-3,4-dihydro-3-dichloromethyl-6-nitro-7-sulfamyl-1,2,4-benzothiadiazine-1,1-dioxide.

9. 2-ethyl-3-chloromethyl-3,4-dihydro-7-sulfamyl-6-nitro-1,2,4-benzothiadiazine-1,1-dioxide.

10. 3,4-dihydro-2-ethyl-6-nitro-3-(β -oxo- β -phenyl-ethyl)-7-sulfamyl-1,2,4-benzothiadiazine-1,1-dioxide.

11. 3-benzyl-3,4-dihydro-6-nitro-7-sulfamyl-2-(β,β,β -trifluoroethyl)-1,2,4-benzothiadiazine-1,1-dioxide.

12. 3-dichloromethyl-3,4-dihydro-7-sulfamyl-2-(β,β,β -trifluoroethyl)-6-nitro-1,2,4-benzothiadiazine-1,1-dioxide.

13. 3-chloromethyl-3,4-dihydro-6-nitro-7-sulfamyl-2-(β,β,β -trifluoroethyl)-1,2,4-benzothiadiazine-1,1-dioxide.

14. 3,4-dihydro-3-(β -ketopropyl)-6-nitro-7-sulfamyl-2-(β,β,β -trifluoroethyl)-1,2,4-benzothiadiazine-1,1-dioxide.

15. 3,4-dihydro-2-ethyl-3-(β -ketopropyl)-6-nitro-7-sulfamyl-1,2,4-benzothiadiazine-1,1-dioxide.

16. 3-dichloromethyl-3,4-dihydro-2-ethyl-6-nitro-7-sulfamyl-1,2,4-benzothiadiazine-1,1-dioxide.

17. 2-benzyl-3-dichloromethyl-3,4-dihydro-6-nitro-7-sulfamyl-1,2,4-benzothiadiazine-1,1-dioxide.

18. 2-lower alkyl-3,4-dihydro-6-nitro-3-haloalkyl-7-sulfamyl-1,2,4-benzothiadiazine-1,1-dioxide.

19. 2-phenyl-lower alkyl-3,4-dihydro-6-nitro-3-haloalkyl-7-sulfamyl-1,2,4-benzothiadiazine-1,1-dioxide.

75 20. 2-phenyl-lower alkyl-3,4-dihydro-6-nitro-3-haloalkyl-7-sulfamyl-1,2,4-benzothiadiazine-1,1-dioxide.

11

20. A pharmaceutical composition in unit dosage form
containing 5 to 500 mgm. of a compound of claim 1.
